UNITED STATES PATENT OFFICE.

EDWARD THOMAS JONES, OF NEW ORLEANS, LOUISIANA, ASSIGNOR TO WIRED RADIO INC., OF NEW YORK, N. Y., A CORPORATION OF DELAWARE.

ELECTRICAL REPRODUCER FOR PHONOGRAPH RECORDS.

Application filed November 25, 1921. Serial No. 517,554.

To all whom it may concern:

Be it known that I, EDWARD THOMAS JONES, a citizen of the United States, residing at New Orleans, in the parish of Orleans and State of Louisiana, have invented a certain new and useful Improvement in an Electrical Reproducer for Phonograph Records, of which the following is a specification.

10 My invention relates broadly to phonographs and more particularly to means for reproducing phonograph records.

The object of my invention is to provide an electrical reproducer for phonograph records arranged to reproduce sound records at sufficient amplitude to be heard throughout the area of large halls, auditoriums and amphitheaters and in the open air and wherever the usual phonograph is incapable 20 of reproducing sounds with sufficient volume to satisfy such occasions.

A further object of my invention is to provide an electrical reproducer which eliminates scratching and other external mechanical noises due, among other things, to the mechanical vibration of the parts of the usual sound box reproducer.

A still further object of my invention is to provide a phonograph with means by 30 which the tone and the volume of the music may be varied at the will of the operator.

Heretofore in the reproduction of phonograph music by electrical reproducers, it has been proposed to employ a microphone 35 mounted upon the tone arm of the phonograph and actuated by the stylus of the reproducer. In other cases magneto inductive systems have been proposed in which the tracing stylus imparts vibrations to a metallic armature arranged to vary the magnetic reluctance of the reproducing circuit. All of these prior adaptations have inherent 40 disadvantages due to complications in construction and in the case of the microphone 45 transmitter inherently poor electrical characteristics.

The present invention will be more clearly understood by reference to the following 50 specification and the accompanying drawings in which Figure 1 is a diagrammatic view of my electrical reproducer system for phonographs; Fig. 2 illustrates on an enlarged scale a hill and dale cut sound record; Fig. 3 shows on an enlarged scale a 55 transversely cut groove of a phonograph

record, both types of which are adapted to be employed with the present electrical reproducer; Fig. 4 represents connections for distributing phonograph music by line wire to a number of subscribers; Fig. 5 is a plan view of one embodiment of my invention; and Fig. 6 is a side view of this form of reproducer with the casing partially broken away to show the interior.

It will be understood that the invention 65 may be varied in its details of construction and that the specific embodiment illustrated and described herein is only indicative thereof.

Referring particularly to Fig. 1 of the 70 drawings, reference character 1 represents a phonograph cabinet having a record table 2 supporting a disc record 3. Carried by a swivel mounting upon cabinet 1 is an electrical reproducer 4 comprising stylus point 75 5 secured in holder 6 and secured to lever 7 pivoted upon pivot member 8 at 9 and 10 upon mounting 11. The lever 7 is arranged to mechanically vibrate a wound armature 12 in accordance with the motion of stylus point 5 through a system of levers 36 and 37. The wound armature 12 comprises a large number of turns of fine wire supported 80 on axis 39 mounted within a strong concentrated magnetic field of force emanating from field magnets 14 and 15 carried by mounting 11. A stationary iron core 38 is mounted on the frame 11 within the area covered by the swinging coil 12 to complete the magnetic circuit and increase the magnetic flux cutting the coil. The axis 39 is 85 pivotally mounted on springs 34 and 35 which provide terminals for electrical connections to the armature. The field magnets 14 and 15 are energized by winding 16 and 17 respectively, by a source of energy 18 through adjustable rheostat 19.

Connections are taken from the wound armature 12 within the magnetic field to a primary winding 20 of transformer 21, the secondary 100 22 of which connects to the input circuit of vacuum tube 23 arranged to amplify the energy generated by the mechanical movement of armature 12 in the magnetic field of magnets 14 and 15. The vacuum tube 23 has its output circuit associated with the input circuit of vacuum tube amplifier 24 through transformer 25 forming a second stage of amplification of the energy 105 generated in armature winding 12. The out- 110

put circuit of vacuum tube amplifier 24 is connected to a loud speaker reproducer 26 having an external source of energy 27 for the adjustment of its field. The degree of incandescence of the filaments of the vacuum tubes 23 and 24 may be regulated by rheostats 32 and 33 respectively, whereby the degree of amplification and volume of reproduced music may be varied at will. 10 The loud speaker reproducer 26 is mechanically mounted with reproducing horn 28 through which music is conveyed from the phonograph at opening 29. The electrical reproducer is adapted for 15 operation with a record of either the vertically cut groove type as shown in Fig. 2, wherein the stylus 5 is vibrated mechanically over the hill and dale surface 30; or the record may be of the transversely cut groove 20 type indicated in Fig. 3, wherein the stylus 5 is mechanically actuated by the walls 31 of the record groove.

The armature 12 may be provided at its terminals or through its amplifier leads with 25 terminals A B and connections taken to different forms of reproducers and responsive devices. By means of this electrical reproducer the distribution of music by line wire to different subscribers is accomplished by 30 such a connection as indicated in Fig. 4. The music from an ordinary phonograph record reproduced electrically by the reproducer above described may be furnished to many house subscribers or amusement places such 35 as #1, #2, #3, and #4 by line wire connected in parallel at the terminals A B. A scientific study of phonograph records can be conducted by the connection of a printing tape recorder at the terminals A B by which 40 a vibratory line record permits an indication of the varying frequency of the musical selection. A visible study of the variation and modulation of the musical selection can be made by connecting a frequency meter at 45 the terminals A B interposing the necessary

amplification in the line. The reproducer is particularly adapted for office dictating machines connected in circuit with a vacuum tube amplifier and a receiver which may be provided with a stethoscope worn by the 50 dictaphone operator.

Figures 5 and 6 represent one embodiment of the invention in which the reproducer is mounted in casing 40 upon swivel arm 41 and is adapted to move over record 42 from 55 a central pivot 43 on the phonograph cabinet. Similar characters of reference indicate like parts in these figures as in Figure 1. The terminals of the wound armature 12 are brought out to binding posts 12^a while 60 the terminals of the field magnets are brought out to binding posts 16^a.

In the operation of this apparatus the stylus point 5 of the reproducer is mechanically vibrated in accordance with the impressions upon the phonograph record. The armature coil 12 is vibrated through its system of levers and its windings cut the magnetic field of magnets 14 and 15, generating 65 energy therein in accordance with the musical vibrations which energy is amplified by the vacuum tube amplifier and thrown out to an audience at great volume.

Having thus described my invention what I claim and desire to secure by Letters Patent of the United States is:

In a phonograph transmitter, a casing carried by an arm pivotally mounted relative to a sound record, a pair of bearings on said casing, a motion multiplying lever 80 pivotally mounted in said bearings, a stylus carried by said lever on one side of said pivotal mounting, a coil vibrated by said lever on the opposite side of said pivotal mounting, a permanent magnetic field surrounding said coil, and means whereby said stylus mechanically vibrates said coil and generates energy therein.

EDWARD THOMAS JONES.
